UNITED STATES PATENT OFFICE.

TEUNAUSKI Z. CARPENTER, OF PROVIDENCE, RHODE ISLAND, ASSIGNOR TO FEDERAL SCREW CORPORATION, OF PROVIDENCE, RHODE ISLAND, A CORPORATION OF RHODE ISLAND.

SCREW-THREADING MACHINE.

1,143,942.

Specification of Letters Patent. Patented June 22, 1915.

Application filed August 28, 1912. Serial No. 717,522.

To all whom it may concern:

Be it known that I, TEUNAUSKI Z. CARPENTER, citizen of the United States, and resident of Providence, in the county of Providence and State of Rhode Island, have invented certain new and useful Improvements in Screw-Threading Machines, of which the following is a specification.

This invention relates to improvements in screw threading machines, and has for its object to provide such a machine with mechanism having a transferring member for receiving the blank from a suitable feed and depositing its head between the jaws of a rotatable chuck, to then operate a pointing device to reduce or point the end of the screw blank, to next position a back rest to support the blank while the thread is being formed thereon by a suitable cutter and to provide a gripping member for engaging and binding the finished screw to the back rest and to cause the back rest to move longitudinally to remove the screw from the jaws and finally to withdraw the gripper to deposit the finished screw.

The invention consists essentially of the gripper member carried by the back rest which is adapted to engage and bind the finished screw to the rest and also the mechanism for moving the back rest, its gripper and the screw carried thereby longitudinally to subsequently release the screw to be deposited. By this construction the rest performs a double function, first it supports the blank while being cut, and second, it serves to assist in removing the finished screw. By this movement it will be seen that the back rest is carried completely out of the way to permit the quick action of the mechanism to deposit a fresh blank into the jaws to be cut, without waste of time.

With these and other objects in view, the invention consists of certain novel features of construction, as will be fully described and particularly pointed out in the appended claims.

Of the accompanying drawings, Figure 1— is a side elevation showing the general arrangement of mechanism for operating a screw cutting machine. Fig. 2— is an enlarged plan view of a portion of the operating mechanism. Fig. 3— is a sectional elevation on line 3—3 of Fig. 2 looking in the direction of the arrow. Fig. 4— is a detail illustrating the cam mechanism for im-

parting a longitudinal motion to the back rest. Fig. 5— is a detail of the cam for operating the pointer mechanism. Fig. 6— is a detail of the cam for operating the screw gripping finger showing a portion of the back rest in section. Fig. 7— is a detail of the cam which operates the mechanism for carrying the screw from its supply fountain to the point where it is engaged by the transferrer fingers. Fig. 8— is a detail side elevation of the cam for operating the transferrer fingers. Fig. 9— is an edge view of the cam shown in Fig. 8.

Referring to the drawings, 10 shows a general frame construction in which the operating mechanism is mounted, the upper portion of which is shown as supporting a hopper 11 of any suitable construction and is illustrated as being partly broken away. From this hopper the screw blanks are fed by suitable means down the channel 12 of the fountain 13 and are deposited into the carrier 14, see Fig. 3, which carrier is reciprocated by the cam 15 mounted on shaft 31, see also Fig. 7, through the finger 16, 80 arm 17 and connection 18 to move the blanks one at a time from the fountain out to the position 19 as illustrated in Fig. 3 where each blank is engaged by the transferrer fingers 20, which is actuated by the cam 21, 85 see also Fig. 8, mounted on shaft 31, pin 22, finger 23 and arm 24, to first raise the blank out of engagement with the carrier by the rise 25 of the cam 21, then dropped to the position 26, see Fig. 3, into alignment with the central opening between the jaws 27 of the chuck 28, see Fig. 1, and when moved to this position the cut away side face of the cam 29, as best illustrated in Fig. 9, is presented and permits the fingers 23 and arm 24 under pressure of the spring 30, to move longitudinally a distance sufficient to pass the head of the blank between said chuck jaws 27, Fig. 3 after which the continued rotation of the cam 21 again raises the transferrer fingers to repeat the operation just described.

The next operation after depositing the blank into the jaws is that the cam 32 on its shaft, see Fig. 1, is rotated through the gears 32^a and by oscillating the lever 33 permits the jaws of the chuck 28 under action of the spring 34 to close upon the head of the screw blank to rotate the same. The next action of the machine is to advance 110

a pointing cutter 35 onto the end of the rotating blank for the purpose of reducing or pointing the same. This cutter is slidably mounted see Fig. 2, to move longitudinally in the frame at 36 and is connected through the arm 37 to the slidable bar 38, to move therewith which bar is provided with a downwardly projecting pin 39 adapted to engage the portion 40 of the cam 41 whereby the rotation of said cam at the proper time advances the cutter to engage and point the end of the screw blank. After the blank has been thus pointed the pin 39 engages the portion 42 of this cam and is quickly withdrawn removing the pointing cutter. This bar is also provided with a forwardly extending block 43 which has a beveled face 44. An upwardly extending back rest 45 is mounted on the shaft 46 which shaft is moved endwise by the cam 47 mounted on the shaft 31 through the forked lever 48 pivoted at 49, one end of which lever is adapted to project into the groove of cam 47 while the forked end 50 engages the groove in collar 51 fixed to the end of shaft 46. Extending rearwardly from the upper end of this back rest in the same plane with the beveled block 43 is a similar beveled block 52 adapted to coöperate with that on the bar 38 in the manner hereinafter described. This back rest is provided with a central recess 53 see Fig. 6 and has a pair of rearwardly projecting ears 54 in which ears is pivotally mounted an arm 55 on the pivot pin 56. To the upper end of this arm 58 is pivoted an upwardly extending grip finger 57, said finger being held normally in contact with the front face of the back rest by a coil spring 59. The opposite end of this finger arm is cut away slightly and adapted to be engaged by the pin 60 in the collar 61 mounted to rotate with shaft 31. In the upper end of this back rest is shown a central block 62 provided with grooves of different sizes to fit screws of different dimensions, said block being held in position by means of a cap 63 and screw bolt 64, the screw to be threaded being shown in position at α .

As illustrated in the drawing when the pointer cutter see Fig. 2, is advancing, the bar 38 with its cam 43 is also being moved to the right, and the back rest through its cam is likewise being moved to the right to its position back of the screw blank, but swung back to its inoperative position out of line and out of the way of the pointer 35. As this pointer cutter after finishing its pointing operation together with the bar 38 is being moved back to its inoperative position illustrated in Fig. 2, the beveled portion of block 52 engages that of the block 43 and the rest is brought forward so as to engage the back portion of the blank and support the same while being threaded by the cutter.

The cutter 65 is held in the head 66 and is given a suitable longitudinal motion by any suitable mechanism (not shown) the cuts to form the thread being controlled see Fig. 3, by means of the usual former 71 and a cam 70 75 70 which latter is provided with a series of rises each succeeding one being a little higher than the other so that each succeeding cut of the cutter will be a little deeper than the one preceding until the desired number and depth of cuts have been taken to form the required screw thread, after which the finger 68 will fall down into the elongated recess 69, see Fig. 3, raising the point of the cutter from its work, for a sufficient interval 80 to permit the removal of the finished screw and the deposit of a new blank into the chuck to be acted upon. This removal operation may be further explained as follows:—
 As soon as the threading cutter is withdrawn the pin 60 see Fig. 6, on the collar 61 engages the lower end of arm 55 and immediately moves the gripper finger 57 up into yielding engagement with the finished screw to bind and hold the same in the little 85 90 socket in the block 62. The cam 32 is now caused to instantly release the jaws of the clutch and the cam 47 acting through the arm 48 moves the back rest to the left a distance sufficient to permit the block 52 to 95 slide off of the block 43 thereby permitting the back rest under action of spring pin 70, see Fig. 3, to drop back out of the way of the next forward stroke of the pointer, at the same time the pin 60 has moved to the 100 very end of and released the arm 55 to return under action of the spring 59 to its normal position and to withdraw the gripper finger 57 from engagement with the screw permitting the latter to fall by gravity into 105 a suitable receptacle beneath. It will be noted that by this construction no time is lost as the screw is positively removed from its position in the jaws and the removal action of the back rest also carries this rest 110 out of the way so as to permit the quick deposit of another blank into the jaws, after which the action of the mechanism is repeated as above described and by which the screws are formed on the screw blanks very 115 rapidly and accurately and no time is lost between the successive operation.

I claim:

1. In a screw threading machine, means for receiving and rotating the blank, means for cutting threads on the blank, a rest for supporting the blank while being cut, and means coöperating with the rest for engaging and removing the screw from the chuck when finished.
2. In a screw threading machine, means for receiving and rotating the blank, means for cutting threads on the blank, a rest for supporting the blank while being cut, means carried by said rest for engaging and bind- 125 130 135 140 145 150 155 160 165 170 175 180

ing the finished screw to said rest, and means for moving said rest to remove said screw from said chuck.

3. In a screw threading machine, means 5 for receiving and rotating the blank, means for cutting threads on the blank, a rest for supporting the blank while being cut, and means including said rest for removing the screws from the chuck when finished.

10 4. In a screw threading machine, a rotatable chuck, means for depositing screw blanks into the jaws of said chuck, a cutter for threading the blank, a back rest, means for moving said rest to support the blank 15 while being cut, means for removing the cutter after having cut the blank, means for binding the finished screw to the rest, means for causing said chuck to release the screw, means for moving the rest and screw from 20 said jaws, and means for subsequently removing said binding means to release and deposit the screw.

5. In a screw threading machine, a rotatable chuck, means for depositing screw 25 blanks into the jaws of said chuck, a cutter for threading the blank, a back rest, means for moving said rest to support the blank while being cut, means for removing the cutter after having cut the blank, a finger 30 carried by said chuck, means for moving said fingers to engage and bind the finished screw to the rest, means for moving the rest and screw thus held from said jaws, and means for subsequently withdrawing said 35 finger to release and deposit the screw.

6. In a screw threading machine, a rotatable chuck, means for depositing screw blanks into the jaws of said chuck, a cutter for threading the blank, a back rest, means 40 for removing said rest from the work while it is being pointed, means for moving said rest to support the blank while being threaded, means for removing the cutter after having threaded the blank, a finger 45 carried by said chuck, a rotatable member for moving said finger to engage and bind the finished screw to the rest, means for moving the rest and screw thus held from said jaws, and means for subsequently withdrawing said finger to release and deposit the screw.

7. In a screw threading machine, a rotatable chuck, means for depositing screw blanks into the jaws of said chuck, a cutter for threading the blank, a back rest, means for removing said rest from the work while it is being pointed, means for moving said rest to support the blank while being threaded, means for removing the cutter 60 after having threaded the blank, a finger carried by said chuck, a rotatable member for moving said finger to engage and bind

the finished screw to the rest, a cam for moving the rest and screw thus held longitudinally from said jaws, and means whereby said finger is arranged to disengage said fingers and permit it to release and deposit the screw. 65

8. In a screw threading machine, a rotatable chuck, means for depositing screw 70 blanks into the jaws of said chuck, a cutter for threading the blank, a back rest, means for moving said rest to support the blank while being threaded, means for removing the cutter after having threaded the blank, 75 and a spring controlled finger normally withdrawn carried by said rest, a rotatable member arranged to raise said finger to engage and bind the finished screw to the rest, means for removing the rest and screw thus 80 held longitudinally from its jaws, and means whereby such movement causes said finger to be released by its cam to return to normal and release the screw.

9. In a screw threading machine, a rotatable chuck, means for depositing screw 85 blanks into the jaws of said chuck, a cutter for threading the blanks, a back rest, a cam for moving said back rest longitudinally and a second cam for moving said rest forward to engage and support the screw while being cut, means for withdrawing the cutter after threading the blank, a gripper carried by said rest, means for moving said gripper to engage and bind the finished screw to the 95 rest, means for moving said rest with its screw from engagement with said second cam to move backward, and means for removing the gripper to release the screw. 90

10. In a screw threading machine, a rotatable chuck, means for depositing screw 100 blanks into the jaws of said chuck, a cutter for threading the blanks, a back rest, means for removing said rest from the work while it is being pointed, a cam for moving said 105 back rest longitudinally and a second cam for moving said rest forward to engage and support the screw while being threaded, means for withdrawing the cutter after threading the blank, a gripper carried by 110 said rest, a rotatable member for moving said gripper to engage and bind the finished screw to the rest, a cam for moving said rest longitudinally out of engagement with said second cam, means for moving said rest backward out of line with said blank pointer, and means for causing said gripper actuating mechanism to release the screw. 115

In testimony whereof I affix my signature in presence of two witnesses.

TEUNAUSKI Z. CARPENTER.
